UNITED STATES PATENT OFFICE.

DOMINICK SPRADA, OF BUFFALO, NEW YORK.

SPARK PLUG.

Application filed May 24, 1923. Serial No. 641,084.

To all whom it may concern:

Be it known that I, DOMINICK SPRADA, a citizen of the United States, residing at Buffalo, in the county of Erie and State of New York, have invented certain new and useful Improvements in Spark Plugs, of which the following is a specification.

My invention relates to improvements in spark plugs for internal combustion engines, and one of its objects is to provide a new and novel device of that character having a plurality of sparking gaps so arranged and the electrodes forming the same are so supported that the possibilities of the accumulation of carbon or other matter tending to foul the same will be reduced to the minimum.

It also has for its object the provision of a spark plug having an axial electrode provided with an insulation terminal of considerable size, which is spherical in formation and preferably glazed and through which a plurality of electrodes extend for co-operation with the axial electrode and with the shell of the spark plug.

With the above and other objects in view, the invention consists in the novel features of construction, and in the arrangement and combination of parts to be hereinafter described and more particularly pointed out in the subjoined claims.

In the drawings:—

Fig. 1 is a sectional elevation of a portion of an automobile, showing the engine thereof equipped with my improved spark plug.

Fig. 2 is a side elevation of one of the spark plugs.

Fig. 3 is a top plan view of the same.

Fig. 4 is an enlarged longitudinal section taken on line 4—4, Fig. 3.

Fig. 5 is an enlarged longitudinal section taken on line 5—5, Fig. 2.

Fig. 6 is an enlarged transverse section taken on line 6—6, Fig. 4.

Referring to the drawings in detail, the reference numeral 7 designates an automobile having an engine 8 provided with spark plugs 9 arranged according to my invention.

My improvements are shown applied to a spark plug of common construction, but it is to be understood that such improvements may be applied to spark plugs of various kinds.

10 designates the casing of a spark plug, the casing shown in the drawing having an internal flange 11 between its ends. The

upper or outer end of said casing is internally threaded, as at 12, and the other or inner end is slightly tapered and externally threaded, as at 13.

14 designates an insulating core inserted into the casing from the upper end and having a collar 15, said collar being adapted to receive support from the flange 11 of the casing; a suitable gasket 16, however, is interposed between said flange and collar. The lower portion of said core is reduced in diameter and extends inwardly through the opening formed by the flange 11. A nut 17 is threaded into the upper end of the casing 10, and between said nut and collar 15 of the core, a suitable gasket 18 is interposed. Upon tightening said nut 17, it will be forced against the collar 15 of the core, with the gasket 18 between the two, at the same time forcing said collar 15 against the internal flange 11 of the casing, with the gasket 16 between the two, thus establishing an air-tight connection between the core and casing.

The core extends upwardly above the nut 17 and it has an electrode 19 extending axially therethrough, the upper or outer end of which receives a screw nut 20 by means of which a current conducting wire may be connected to said electrode in the usual manner. The core insulates the electrode from the casing 10, which is grounded, as is common.

The casing 10 is provided at one side with a threaded opening 21 into which an elbow extension 22 of a valve casing 23 is threaded, said valve casing having an upward extension in the form of a cup 24. A passage 25 leads through said valve casing from said cup 24 to the interior of the spark plug 10. Within the valve casing is a valve plug 26 through which a passage 27 is formed, said passage being normally out of alignment with the passage 25 of the valve casing. The valve plug is disposed at right angles to the passage 25, and has connected to one end thereof a lever 28. Within the elbow extension the passage 25 is enlarged, as at 40, forming a shoulder 41 serving as a valve seat, and in this enlarged portion of the passage is a valve, preferably a ball valve 42, which is free to move back and forth therein within a limited range. In order to prevent the ball valve from entering the spark plug casing, or being drawn thereinto by the suction of the piston within the cylinder to

which the spark plug is secured, a stop pin 43 is passed transversely through the elbow extension. The ball valve 42 is therefore free to move within the enlarged portion of 5 the passage 25 between the valve seat 41 and the stop pin 43. Therefore, when the valve plugs 26 are opened to any desired degree, air is drawn through the spark plugs and into the cylinders during the suction stroke 10 of the pistons within the cylinder, and during the compression strokes of said pistons said ball valves are forced against their seats 41 and prevent the escape of the explosive mixture through the plugs.

15 In an automobile, the spark plugs are normally arranged in line, and when so disposed, the levers 28 of all the spark plugs are connected together by means of a rod 29, which extends rearwardly beyond the 20 rearmost spark plug and has one end of a lever 30 secured thereto, said lever being pivotally secured between its ends to a bracket 31 fastened to the dashboard 32. The opposite end of said lever is pivotally 25 connected to an actuating rod 33 extending rearwardly through said dashboard and through the instrument board 34, it having a knob or handle 35 at its rear end adapted to normally bear against said instrument 30 board. With such parts in the position shown in Fig. 1, the valve plugs 26 in the valves applied to the spark plugs have their passages 27 at right angles to the passages 25 extending through the valve casings, thus 35 closing the lower or inner portions of the passages leading to the interior of the spark plugs.

If it is desired that air be drawn into the 40 cylinders of the engine on the suction stroke of the pistons therein for the purpose of mixing the same with the explosive mixture drawn into said cylinders, the valve plugs or, more broadly considered, the valves, may be opened to the desired degree, it being 45 simply necessary to pull rearwardly on the actuating rod 33, whereupon the levers of the valves will be swung through an arc of a circle and the valve plugs rotated within the valve casings until the passages through 50 said plugs register or partly register with the upper and lower portions of the passages through the valve casings, as may be desired.

In cold weather it may also be desirable 55 to prime the automobile, which is usually done by removing the spark plugs and pouring gasoline into the cylinders, and where spark plugs have heretofore been equipped with valves individually operated, it was necessary to open one valve after the other 60 in order to deliver gasoline into the cylinders. By the time gasoline is delivered to all of the cylinders, the valves closed, and the operator has returned to his seat to start the engine, considerable of the gasoline will 65 be allowed to find its way downwardly into

the crank casing of the engine, and under such conditions the gasoline remaining in each cylinder as a thin film, will have lost more or less of its effectiveness.

With this invention, gasoline may be 70 placed in the cups 24 of the valves and the operator can enter the automobile and start the same. Immediately upon rotating the engine shaft with his starter, he may grasp the handle 35 and draw the rod 33 rearwardly, whereupon gasoline will be delivered into the engine cylinders, and in at least one or more of them such delivery 75 will take place at the moment that a spark is established therein by means of the spark 80 plug threaded thereinto. It will be apparent therefore that by having means on the spark plugs to retain a quantity of gasoline, and means to deliver said gasoline at the time of starting the same, the engine will start 85 more readily than with the common form of priming devices now in use.

After the gasoline is delivered through all of the spark plugs, the actuating rod may be pushed forwardly to close the valves; or, 90 the valves may be kept open to any desired extent by adjusting the actuating rod, and thus air can be drawn into the spark plug and explosive chamber of the engine to be 95 mixed with the explosive mixture.

The electrode 19 extending through the core has a porcelain or other insulation terminal 36, of considerable size, the same being spherical in formation and preferably glazed, and the extremity of said electrode 100 is provided with a head 37 to prevent said spherical insulator from becoming detached. Extending through said insulator 36 are a plurality of electrodes 38 arranged parallel 105 with said electrode 19 and they preferably have their upper ends curved toward the electrode 19 to form spark gaps between the two, which gaps serve as intensifiers for the current passing through the spark plugs.

39 designates an electrode, which extends 110 transversely underneath the spherical insulator 36, said electrode 39 being underneath and having one arm secured in the wall of the spark plug casing, and the other arm extending in a diametral direction so 115 as to lie between the lower terminals of the plurality of electrodes 38. The electrodes 38 may also have their lower ends bent inwardly, or toward the electrode 39, and between the electrodes 38 and 39 sparking gaps 120 are provided, said gaps being wholly outside of the spark plug casing so that when said casing is threaded into the engine cylinder, the effective sparks at the last-mentioned 125 spark gaps will occur within said engine cylinder, while the intensifying sparks take place within the spark plug casing.

In the drawings I have shown four electrodes 38, but any other number may be 130

employed, as the use of a spherical insulator at the lower end of the axial electrode 19 will enable any desired number of sparking electrodes to be used by merely positioning them at desired points through said spherical insulator and around the electrode 19. By the use of a spherical insulator, all portions thereof are rounded and lodgment of carbon or other foreign matter cannot so readily take place. Moreover, by breaking the current before reaching the effective spark gaps so that the current must jump through space, it is intensified considerably at the effective spark gaps between the lower ends of the electrodes 38 and the electrode 39; thus assuring effective explosion.

Having thus described my invention, what I claim is:-

1. A spark plug comprising a casing, an insulation core within said casing having an axial electrode provided at its inner end with a glazed spherical insulator, and an electrode extending through said spherical insulator and in sparking relation to said axial electrode and to said casing.

2. A spark plug comprising a casing, an insulation core within said casing having an axial electrode, a spherical insulator mounted on the inner extremity of said axial electrode, and a plurality of electrodes extending through said spherical insulator, the inner end of each of said plurality of electrodes being in spaced relation to said axial electrode and the outer ends thereof being in sparking relation to said casing.

3. A spark plug comprising a casing, an insulation core within said casing having an axial electrode provided at its inner end with a spherical insulator, a second electrode extending from said casing, and a plurality of electrodes extending from said spherical insulator and in sparking relation to said

second electrode, said plurality of electrodes being in current-conducting relation to said axial electrode.

4. A spark plug having a casing, an insulation core extending into said casing and having an axial electrode, a spherical insulator secured to the inner end of said axial electrode, a plurality of electrodes in intensifying relation to said axial electrode and extending beneath said spherical insulator, and an electrode carried by said casing and in sparking relation to said plurality of electrodes.

5. A spark plug comprising a casing, an insulation core within said casing having an axial electrode extending therethrough, a spherical insulator at the inner end of said axial electrode, a plurality of electrodes parallel with said axial electrode and having one of their ends in spaced but current-conducting relation to said axial electrode, and an electrode extending inwardly from said casing and disposed in spaced relation to said spherical insulation, said last-mentioned electrode being in sparking relation to said plurality of electrodes.

6. A spark plug comprising a casing, an insulation core fitting in said casing and having an axial electrode extending therethrough, the inner end of said electrode having a head, a spherical insulator secured to the headed inner end of said electrode and having a plurality of parallel electrodes extending therethrough and projecting in opposite directions therefrom, the inner projecting ends being in current-conducting relation to said axial electrode, and an electrode connected to said casing and being in sparking relation to the opposite ends to said plurality of electrodes.

In testimony whereof I affix my signature.
DOMINICK SPRADA.
